UNITED STATES PATENT OFFICE.

EDWIN M. ROSENBLUTH, OF PHILADELPHIA, PENNSYLVANIA.

DESIGN FOR AN ACETYLENE-GAS-GENERATOR BODY.

No. 39,255.

Specification for Design.

Patented April 7, 1908.

Application filed January 17, 1907. Serial No. 352,834. Term of patent 14 years.

To all whom it may concern:

Be it known that I, EDWIN M. ROSENBLUTH, of Philadelphia, in the county of Philadelphia and State of Pennsylvania, have invented a new, original, and ornamental Design for Acetylene-Gas-Generator Bodies, whereof the following is a specification, reference being had to the accompanying drawing.

Said drawing shows a perspective view, of

an acetylene gas generator body showing my new design.

I claim:

The ornamental design for an acetylene gas generator body as shown.

EDWIN M. ROSENBLUTH.
